UNITED STATES PATENT OFFICE.

LEONARD S. BEST, OF SUISUN, CALIFORNIA, ASSIGNOR OF ONE-HALF TO JOHN J. BIRMINGHAM, OF SUISUN, CALIFORNIA.

DISH-WASHING MACHINE.

1,240,298.

Specification of Letters Patent. Patented Sept. 18, 1917.

Application filed August 28, 1916. Serial No. 117,189.

To all whom it may concern:

Be it known that I, LEONARD S. BEST, a citizen of the United States, residing at Suisun, in the county of Solano and State of California, have invented a new and useful Improvement in Dish-Washing Machines, of which the following is a specification.

This invention consists of a dish washing machine.

10 One of the objects of the present invention is to provide a simple, cheaply manufactured, easily operated dish washing machine, comprising a container provided with dish supporting racks so arranged and positioned within the container that the dishes supported thereby may be cleaned by the flushing action of a cleansing liquid such as soap water or the like.

Another object of the invention is to provide a novel form of removable dish supporting rack, and furthermore to provide an impeller to maintain a continuous and violent circulation of the cleaning liquid between the dishes.

25 Further objects will hereinafter appear.

The invention consists of the parts, and the construction and combination of parts as hereinafter more fully described and claimed, having reference to the accompanying drawing in which:—

Figure 1 is a central vertical section through the dish washing machine.

Fig. 2 is a plan view showing a cover removed.

35 Fig. 3 is a perspective view of one form of dish supporting rack employed.

Fig. 4 is a similar view of another form of rack.

Referring to the drawings in detail, A 40 indicates a cylindrical shaped tank provided with a sloping bottom 2, and a central recessed section 3. Mounted interior of the tank and centrally positioned therein, is a shaft 4 upon which is secured an impeller 45 5 hereinafter to be described.

The lower end of the shaft 4 projects through the central recessed portion 3 in the bottom and is here supported in a pair of bearing members 6 and 7, one of 50 said bearings being secured on the bottom of the container, and the other in a bracket 8. Secured on the shaft intermediate of the bearings 6 and 7 is a driving pulley 9 to which power may be transmitted in any suitable manner and connected with a discharge

opening formed in the central recessed section 3 is a valve 10 which may be opened when it is desired to empty the tank.

The tank proper may be supported upon legs 11 or any convenient frame, and it is 60 furthermore provided with a cover 12 which may be removed to fill the tank with soap water or any other cleaning medium and also for the purpose of inserting or removing a pair of dish supporting racks 65 such as shown in Figs. 3 and 4. The rack shown in Fig. 3 is semi-circular in shape and consists of a pair of end frames 14 and 15, to which is secured a semi-circular shaped bottom frame 16. Pivots mounted 70 in the frame section 16 is a plurality of wire rings 17 which are adapted to receive and support plates and saucers or like dishes, and for the purpose of preventing said dishes from rolling out between the supporting rings, a plurality of semi-circular side-stays 18 have been provided which are secured to the frame ends 14 and 15.

75 Mounted intermediate of the frame ends 14 and 15 in any position between the rings 17, is an elongated open mesh wire cylinder 80 of holder 19, which is adapted to receive knives, spoons, forks, etc. The rack member shown in Fig. 4 is similarly constructed of two end frames 14 and 15 and connecting 85 wire stays 18 of semicircular shape, but is preferably more open in construction to permit insertion of larger dishes such as platters and the like. These racks when filled with dishes, are lowered into the cylindrical tank A, and are here practically submerged when the tank is filled with soap water or any other cleansing medium. The impeller provided forms one of the important features of the present invention.

90 By referring to Fig. 1 it will be seen that the hub 20 of the impeller is cone shaped, and that the impeller blade consists of one single spiral shaped blade having its largest area at the bottom as indicated at 21, and 100 gradually decreasing as it reaches the upper end of the hub 20. Power applied from any suitable source to the pulley 9 and shaft 4, upon which the impeller is mounted, causes it to rotate with sufficient speed to maintain 105 a continuous and violent circulation of the cleaning medium. The shape of the spiral bladed impeller throws the water in which the dishes are submerged radially in all directions with such violence that the surface 110

of the submerged dishes are readily cleansed in a very few minutes, the open construction of the dish supporting racks being such that water is permitted to penetrate and circulate freely in all directions. The circulation is aided by the inclined annular bottom, and the central depression from which the spiral distributor draws its supply.

In actual operation it has been found desirable to employ two waters, first the tank is filled with soap water which is circulated between the dishes approximately 3 minutes. The impeller is then stopped and the valve 10 opened to permit the tank to be emptied. The tapering bottom and the central recess permitting practically speaking, every drop to be removed. Valve 10 is then closed and the tank again refilled with a rinsing water which is again circulated a few minutes and finally drawn off through the valve 10. This rinsing water should preferably be comparatively hot, as the dishes will be dried by the heat imparted when the water is removed. The individual racks may then be removed and the dishes placed upon the shelves, as wiping with towels for the purpose of drying is not necessary.

The racks constructed as here shown, not only form convenient baskets for carrying the dishes to and from the pantry, but are so open in construction that circulation around every dish or article submerged is permitted.

While soap water has here been mentioned as a cleaning medium, it is obvious that soda, ammonia, or any other grease cutting substance may be added to the water. Simi-

larly while a pulley is shown as connected with the impeller shaft, it is obvious that a direct connected electric motor or hand operated gear drive may be employed if desired.

The materials and finish of the several parts of the machine may otherwise be such as the experience and judgment of the manufacturer may dictate.

I wish it understood that various changes in form, proportions, and minor details of construction may be resorted to within the scope of the appended claim, and that I do not wish to limit myself to the specific design or construction here shown.

Having thus described my invention, what I claim and desire to secure by Letters Patent is:—

In a dish washing machine of the character described, a cylindrical container, having an annular inclined bottom and a depressed central sump, means carried upon the annular bottom around the central sump, to support articles to be washed, a vertical shaft journaled and turnable in the center of the sump, said shaft having an upwardly divergent hub, a spirally disposed blade fixed to the hub, decreasing in diameter upwardly from the bottom, and a motor connecting with the shaft below the sump.

In testimony whereof I have hereunto set my hand in the presence of two subscribing witnesses.

LEONARD S. BEST.
